UNITED STATES PATENT OFFICE.

ARTHUR GIESLER, OF DAYTON, OHIO, ASSIGNOR TO THE PLATT IRON WORKS COMPANY, OF DAYTON, OHIO, A CORPORATION OF OHIO.

TURBINE WATER-WHEEL.

No. 856,948.

Specification of Letters Patent.

Patented June 11, 1907.

Application filed May 31, 1905. Serial No. 263,075.

To all whom it may concern:

Be it known that I, ARTHUR GIESLER, a citizen of the United States, residing at Dayton, in the county of Montgomery and State of Ohio, have invented certain new and useful Improvements in Turbine Water-Wheels; and I do declare the following to be a full clear, and exact description of the invention, such as will enable others skilled in the art to which it appertains to make and use the same, reference being had to the accompanying drawings, and to the letters and figures of reference marked thereon, which form a part of this specification.

15 This invention relates to improvements in turbine water wheel construction.

As preliminary to a description of the invention, it may be stated that there are two well known ways for starting and stopping 20 the turbine wheel. The first construction is called the cylinder gate wheel, in which the wheel is started and stopped through a gate and a chute case. This is the most common form and is only referred to herein for comparison. Secondly, the other construction is called the swivel gate wheel in which the cylindrical gate and chute case are omitted, and substituted therefor, is a certain number of individual swivel plates, which by moving 25 them on their axes, guides the water into the wheel, and at the same time, when moved far enough one way, will close or shut off the water from the wheel, and in moving the 30 other way, will allow the water to pass into the wheel and will guide the water at the same time as before stated. There are a good many constructions to operate these 35 different swivels on a certain wheel, but the great difficulty heretofore experienced is due to too much lost motion in the operations of the swivels, and this in turn, is due to too many links and pins; and on the submerged type of swivels, which have no links or pins, the difficulty is to get at the swivels for 40 45 pairs owing to their being submerged in the flume or wheel housing.

The present invention consists in a construction which enables the operation of all the swivels in unison through the least possible number of parts, and at the same time, the assembling of all these parts on the outside of the flume or wheel housing, which permits a thorough lubrication, adjustment and

inspection of the parts from the outside of the wheel housing.

55 Preceding a detail description of my invention, reference is made to the accompanying drawings, of which—

Figure 1, is a vertical mid-sectional elevation of a water wheel system showing a single 60 wheel. Fig. 2, is an end elevation. Fig. 3, is a sectional view with parts broken away. Fig. 4, is a detached detail view of one of the gate swivels and its operating lever. Fig. 5, is a detail view of a portion of the ring showing 65 the operative positions of the gate swivels.

In a detail description of the invention, similar reference characters indicate corresponding parts.

A designates a water wheel flume or housing. B a single water wheel with its runner mounted upon a shaft C, having suitable bearings.

a designates the assembled parts of a gate swivel, each of which consists of a stem b, to 70 the inner end of which is attached a gate or vane h, and to the outer ends of which is attached a lever c. The stems b are extended on the outside of the wheel housing, and upon these extended stems, the oscillating arms 75 or levers c are likewise connected to said stems on the outside of the wheel housing. The free ends d of said levers c terminate in straight parallel sides which engage parts presently specified and through which parts 80 85 the gates h are operated.

The gates or vanes h control the admission of water to the wheel runner i as shown in Fig. 3. Each assembled piece to-wit, the gates h, stems b and lever c constitutes 90 a complete gate swivel—any number of which may be employed which may be found necessary for the desired size of wheel; it being only necessary to connect the end d of the lever c to a moving mechanism. This 95 moving mechanism in the present case, consists of a ring e which lies on the outside of the wheel housing and is movable in a circular path by any suitable means.

In Fig. 2, the ring e is operated from a 190 governor through a pinion D which engages with a segment gear E on an arm F which is fixed to a shaft G. The said shaft G has a rocker or double lever H and H' which carry connecting rods I and I' which are pivoted 105 to opposite points of the ring e. For each

of the swivel levers *c*, there is provided a circular bushing *f* in the ring *e*, said bushings *f* operating in their seats as the ring moves. The seats for said bushings are counterbored 5 in the ring *e*. The bushings *f* have each a square opening in their outer sides which receive the ends *d* of the lever *c*. The ends of said levers are shaped with the parallel straight sides 10 hereinbefore referred to which engage the similar sides of the openings in said bushings. By this connection, the wearing surface or surfaces between the levers and the bushing are reduced to a minimum and uniformity 15 which insures a durability between the parts and avoids any lost motion between the movements of the ring *e* and the gates. And further, owing to the connections between the levers and the bushings being distributed 20 throughout the parallel sides of the levers lying within the openings in the bushings, and throughout the adjacent sides of said openings; the wear is reduced to a minimum.

25 By imparting movement to the ring to and

from as indicated, all of the swivels will move accordingly and will cause the gates or vanes to admit water to the wheel or exclude it from said wheel. To prevent water from leaking along said stems *b*, proper stuffing 30 boxes *k* are provided in the wheel cover *m*.

Having described my invention, I claim:

In a water wheel, a series of gates mounted upon pins, said pins extending on the outer side of the wheel casing, an actuating ring 35 lying on the outer side of the wheel casing, a series of oscillating arms or levers connected upon the exposed ends of the gate pins, the ends of said arms terminating in straight parallel sides, and a series of oscillating bushings mounted in said actuating ring, said bushings having openings in their exposed ends to receive the ends of said levers substantially as specified.

In testimony whereof I affix my signature, 45 in presence of two witnesses.

ARTHUR GIESLER.
